UNITED STATES PATENT OFFICE.

WILFRID PAUL HEATH, OF CHICAGO, ILLINOIS.

METHOD AND MEANS FOR TUNING RADIORECEIVERS.

Application filed November 13, 1924. Serial No. 749,771.

REISSUED

This invention relates to an improved method and means for actuating the tuning dials of a radio receiving set for tuning it to the wave length of a given broadcasting station, and more particularly relates to such devices operable with sets having a plurality of dials.

Certain types of radio receivers employ a plurality of tuning dials all of which are manipulated tuning in a broadcasting station or in tuning from one station to another. The method employed at present to tune such a receiver usually requires considerable patience, as the various tuning elements employed usually bear a certain relation to one another and must therefore be adjusted to a predetermined position to tune the receiver to the wave length of the desired broadcasting station. To tune such a receiver, requires considerable manipulation of the tuning dials, as the operator is only capable of manipulating two of the dials at one time. Thus to tune the various tuning elements of the receiver into resonance with one another and to the wave length of the desired station, may be a tedious operation and may also require considerable time, and be therefore objectionable, as the ideal method is to tune from one station to another immediately.

An object of this invention therefore is to provide an improved means operable with an ordinary receiving set for tuning all the dials simultaneously tuned to the wave length of the desired station.

A further and more specific object of the invention is to provide such a device demountably secured to the tuning dials, and therefore used as an attachment to an ordinary receiver whereby the tuning dials may be selectively tuned to a predetermined setting for a given station by a single operation.

Other objects of the invention will appear from the following description and the accompanying drawings and will be pointed out in the annexed claims.

In the drawings there has been disclosed a structure designed to carry out the various objects of the invention but it is to be understood that the invention is not confined to the exact structure shown as various changes may be made within the scope of the claims which follow.

In the accompanying drawings forming a part of this specification,

Figure 1 is a view in front elevation of a popular type of receiver showing my invention applied thereto;

Figure 2 is an enlarged detail view of a portion of the receiver showing the improved tuning means demountably secured to one of the dials thereof, and also showing the operating means therefor;

Figure 3 is a sectional view to show the preferred manner of mounting the device on the receiver dial;

Figure 4 is a detail view of the flexible means adapted to be selectively secured to the dial-actuating devices for simultaneously actuating the dials;

Figure 5 is a view showing a slightly modified construction;

Figure 6 is a front view of Figure 5.

In the selected embodiment of the invention here shown there is illustrated an ordinary type of radio receiving set comprising a cabinet 7 having the usual panel 8 on which the usual tuning dials 9 are mounted. The usual graduations or markings 11 are shown on the dials so that the dials may be tuned to a predetermined position in tuning in a broadcasting station. In receivers of the type here shown, the various tuning elements employed in the receiver usually bear a certain relation with respect to one another and it is therefore necessary that each dial must be adjusted to a certain position with relation to the other dials, to tune the receiver to the wave length of a given broadcasting station. This requires considerable manipulation of the dials by the operator before a station can be tuned in as it is impossible for the operator to tune more than two dials at one time. Tuning of such a receiver therefore often requires considerable time and patience on the part of the operator.

The feature of this invention is to provide a simple and inexpensive means which may be applied to any ordinary receiver whereby all of the dials may be simultaneously and selectively adjusted to the wave length of a given broadcasting station. The means provided for this purpose preferably consists of a spider-like member comprising an annular ring 12 having a series of integral spokes 13 connecting it to a hub 14 adapted to be fitted

over the usual knob or finger-grip 15 of the dial 9 as shown in Figure 3. The hub is demountably secured to the knob 15 by such means as the setscrews 16. The hub 14 is 5 also shaped to provide a finger-grip whereby the operator may adjust the dial 9 in the usual manner in locating or logging the various stations. As shown in Figure 2, 10 the annular ring 12 of the spider-like member is preferably of such size that the inside diameter thereof will be relatively larger than the outside diameter of the tuning dial 9 so that the operator may see the usual markings on the dial when tuning in a station. 15

A series of apertures 17 are provided in a portion of the annular ring 12 as particularly shown in Figure 2, and these apertures are preferably spaced to correspond to the 20 markings on the dial and are so arranged that they will be located in that portion of the ring opposite the markings 11 on the dial. The means provided for actuating the spider-like members, and therefore the dials 9, 25 preferably consists in a flexible means connecting together the three dials. As shown in Figure 4, this flexible means preferably consists of a series of cords 18 connected together at one end and secured 30 to a main cord 19 having suitable tabs 21 secured to the lower end thereof upon which the usual call letters of the station may be stamped or marked, as indicated by the letters A, B, C, D and E. The other ends of 35 the cords 18 preferably pass upwardly through a series of apertures 22 provided in the baseboard 23 of the receiver and are detachably secured to the annular ring 12 by means of the apertures 17, preferably by being knotted at 24 therein as shown in Figure 40 3. Thus when the cords have been secured to the rings 12, mounted on the dials, and a downward pull is exerted on the tab 21 all of the dials will be simultaneously actuated or 45 rotated until the aperture, in which the cord being pulled is secured, will be in alignment with the apertures 22 in the baseboard 23 and the axes of the dials 9. A flexible compensating member 25 is interposed in each 50 cord 18 and functions to compensate for any variations in the length of the cords when the tab 21 is pulled downwardly to rotate the dials. Thus when it is desired 55 to rotate the dials to tune in a station, the selected tab 21 will be drawn downwardly until all of the dials come to a stop, a position determined by the predetermined 60 location of the cords 18 on the annular rings 12.

To apply this device to a radio set, the various broadcasting stations are first tuned in by manually operating the dials 9. As soon as a station has been tuned in, the upper ends of the cords 18 will be secured 65 in the apertures of the annular ring 12

located directly opposite the reading on the dials, determined by the stationary marks 26 provided on the panel 8 above each dial. As soon as the cords have thus been secured to the rings 12 the call letters of the station 70 may be marked upon the tab 21 so that the operator will know what tab to pull when it is desired to bring in a certain station. After a number of stations have thus been 75 tuned in and the cords 18 secured to their respective apertures in the annular rings 12 the operator may readily and quickly tune from one station to another by pulling upon the selected tab depending beneath the receiving set. This is of particular ad- 80 vantage in receiving sets employing three or more tuning dials as by its use the dials may quickly be adjusted to a predetermined position without loss of time.

In Figures 5 and 6, there is shown a 85 slightly modified construction wherein a guide block 27 is mounted upon the baseboard 23 beneath each dial. This guide block is provided with a series of apertures 28 through which the cords 18 are passed, 90 as shown in the above mentioned figures. These blocks 27 function to guide the cords in a manner similar to the function of the apertures 22 shown in Figures 1, 2 and 3.

The novel device shown on the drawing is 95 designed as an attachment to an ordinary tuning dial and is demountably secured thereto by means of the setscrews 16. If desired, the device may readily be removed 100 from the dials and the set tuned in the usual manner. It is also to be understood that in place of the spider-like member or attachment, here shown demountably secured to the dial, a special dial may be provided 105 having a marginal edge portion wherein the apertures 17 may be provided as now shown in the annular ring 12. Other means may also be provided for securing the ends of the cords 18 to the annular ring 12 without departing from the invention.

It will be understood that the spider-like 110 rings need not be mounted directly upon the tuning dials, but may be suitably connected thereto as in the rear of these dials.

In the accompanying drawing this novel 115 tuning device is shown as applied to a receiving set employing three tuning dials, but it is to be understood that the device may be used on any type of receiving set, whether employing one or a plurality of tuning dials, by simply varying the number of cords 18 to the number of dials employed. Also, if desired, extension cords (not shown) 120 may be secured to the tab cords 19, thereby providing means whereby the operator may readily and conveniently tune the receiving set from a point remote from the receiver.

I claim as my invention:

1. The combination with a radio set having a plurality of tuning dials, of means for 125

simultaneously moving said dials to set them to indicate a certain combination of characters or figures thereon, said means comprising flexible connections having tabs indicating different stations adapted to be pulled by the operator, and means for transmitting such pull to rotate and set said dials.

2. The combination with a radio set having a plurality of tuning dials, of spiders secured to said dials, each having a group of perforations therein, flexible means adapted to enter said perforations, said flexible means when pulled rotating all of the dials simultaneously to set them to indicate certain figures or characters.

3. The combination with a radio set having a plurality of tuning dials, of spider-like rings mounted on said dials and having groups of perforations therein, each perforation corresponding to a certain figure or character on the dial and setting the dial for such figure or character when the perforation is moved to a point below and in line with the vertical axis of the dial, and means engaging said perforations for shifting all of the dials simultaneously to set them to indicate a certain group of figures or characters.

4. The combination with a radio set having a plurality of tuning dials, of a series of cords and guides therefor arranged adjacent to said dials and having tabs corresponding to the combination of figures or characters for which the dials must be set to tune in a certain station, and means connecting said cords with said dials for rotating all the dials simultaneously to set them for the combination of figures or characters represented by the cord that is operated.

5. The combination with a radio receiving set having a tuning dial, of a flexible actuating member having one end demountably and selectively secured to the tuning dial, said actuating member passing through a stationary guide and having an indicating tab secured to the opposite end thereof, whereby it may be pulled to actuate the tuning dial.

6. The combination with a radio set having a plurality of dials, of tabs representing the logs of different stations, flexible elements connecting the tabs to said dials and adapted to be operated separately to set the dials simultaneously for the log of each station.

7. The combination with a radio set having a plurality of dials, of flexible devices adapted to represent the logs of different

stations and connected for individual movement to said dials for moving them simultaneously to log the desired station.

8. The combination with a radio set having a plurality of tuning dials, of spiders connected thereto and having a group of perforations therein, flexible means connected with said perforations, said flexible means when pulled rotating all of the dials simultaneously to set them to indicate certain figures or combinations.

9. The combination with a radio set having a plurality of tuning dials, of spider-like rings connected thereto and having groups of perforations, each perforation corresponding to a certain figure or character on the dial, and adapted for setting the dial in correspondence to such figure or character when the perforation is moved to a point below and in line with the vertical axis of the dial, and means engaging said perforations for shifting all of the dials simultaneously to set them in correspondence to a certain group of figures or characters.

10. The combination with a radio set having a plurality of tuning dials, of members axially concentric with said dials and having groups of perforations therein, each perforation corresponding to a certain figure or connection on the dial and setting the dial in correspondence to said figure or character when the perforation is moved to a point below and in line with the vertical axis of the dial, and means engaging said perforations for shifting all the dials simultaneously to set them to indicate a certain group of figures or connections.

11. A device of the class described comprising a plurality of rotatable dials, a guide adjacent each dial, flexible dial operating means for each dial connected for rotating the dial in predetermined degree, said flexible means passing through respective guides, and thereafter connected for movement in unison.

12. A plurality of rotatable graduated dials, a series of flexible dial operating means for each dial, each adapted for rotating the dial, in a different degree, corresponding to the graduations of the dial, a common guide for the dial operating means of each dial, one member of each series of means of each dial connected together, after passing through the guides, for movement in unison.

In witness whereof, I have hereunto set my hand this 8th day of November, 1924.

WILFRID PAUL HEATH.
